(57) **CLAIM**

The ornamental design for a handheld traffic signaling device, as shown and described.

DESCRIPTION

FIG. 1 is a front isometric view of the handheld traffic signaling device of the present invention;

FIG. 2 is rear isometric view thereof, rotated 90 degrees from FIG. 1;

FIG. 3 is a front view thereof;

FIG. 4 is a left-side view thereof;

FIG. 5 is a rear view thereof;

FIG. 6 is a right-side view thereof;

FIG. 7 is a top plan view thereof; and,

FIG. 8 is a bottom plan view thereof.
